CLAIM

The ornamental design for an ice cream cone, as shown and described.

DESCRIPTION

FIG. 1 is a front elevational view of an ice cream cone showing my new design, the undisclosed rear being a mirror image;

FIG. 2 is a bottom plan view thereof;

FIG. 3 is a top plan view thereof;

FIG. 4 is a right side elevational view thereof, the undisclosed left side being a mirror image; and

FIG. 5 is a cross-sectional view thereof, taken along line 5—5 of FIG. 1.
